DYEING MACHINE

Dominick Potts, Maspeth, Long Island, N. Y.

Application June 15, 1938, Serial No. 213,886

2 Claims. (Cl. 68—188)

This invention relates to a dyeing machine for dyeing wool, rayon, cotton and the like, the general object of the invention being to keep the material immersed in the dyeing liquid at all times, thus insuring a uniform color and penetration to all parts of material by the dyeing liquid.

Another object of the invention is to provide means for supporting the material in loops in the machine with means for slowly turning the loops at intervals and in opposite directions.

Another object of the invention is to provide means for adjusting the lower supporting means of the loops to suit the length of the loops.

This invention also consists in certain other features of construction and in the combination and arrangement of the several parts to be hereinafter fully described, illustrated in the accompanying drawings and specifically pointed out in the appended claims.

20 In describing the invention in detail, reference will be had to the accompanying drawings wherein like characters denote like or corresponding parts throughout the several views, and in which:

Figure 1 is an elevation of the invention showing the frame raised from the tank.

Figure 2 is a longitudinal sectional view through the invention with the frame in place in the tank.

Figure 3 is a transverse sectional view through Figure 2.

30 Figure 4 is a section on the line 4—4 of Figure 1.

Figure 5 is a fragmentary elevation of the means for removably holding the lower rods in place, this view also showing portions of the 35 means for adjusting the lower rod carrying frame vertically.

Figure 6 is an elevation with parts in section showing how the chain is arranged relatively to a toothed wheel.

40 Figure 7 is a fragmentary elevation taken at the opposite side of Figure 6.

Figure 8 is a fragmentary view showing how the notch is formed in the opposite supporting member for the square bars.

45 Figure 9 is a perspective view of one of these bars.

Figure 10 is a fragmentary elevation showing the rack bar and the turn button of the adjusting lever for the frame carrying the lower bars.

50 Figure 11 is a section on the line 11—11 of Figure 10.

Figure 12 is a section on the line 12—12 of Figure 1.

55 In these drawings the letter A indicates the tank which is provided with a short top piece 1

at one end thereof and a vertically arranged transversely extending partition member 2 extending across said end portion of the tank and a horizontal plate 3 covers the top of the space formed by the partition member 2 and the adjacent end wall of the tank. This plate 3 is formed with a large circular opening 5 in its center and a plurality of holes 6 are arranged in the plate between the center hole or opening and each end of the plate. A shaft 6 passes vertically through the top piece 1 and is journaled in the bottom of the tank as shown at 7 and a sleeve 8 is fastened to the shaft and carries a propeller 9 which is located in the lower part of the space formed by the partition member 2 and the adjacent end walls of the tank. A motor M is fastened to the top piece 1 and gears 9 connect the motor shaft with the upper end of the shaft 6. Thus the dyeing liquid placed in the tank will be agitated and caused to circulate and this liquid is heated by steam introduced into the pipes 10 which have horizontal parts 11 in the bottom of the tank which are provided with perforations 12.

A frame B is adapted to be placed in the tank through the open top thereof and to be removed therefrom by means of a suitable hoist to be connected to the stays 13 connected to the stationary parts of a cover C, these stationary parts being connected by uprights 14 to the top of the frame B. The cover C is provided with the hinged doors 15 which carry the eyebolts 16 which are to receive bars for holding the frame from shifting while in the tank.

The frame B includes the four corner posts 17, the two posts at one side of the frame being connected together by a side beam 18 and the other two posts being connected together by a side beam 19. The inner face of the beam 18 has a plurality of vertically arranged slots or grooves 20 therein opening out through the upper edge of the beam and terminating at their lower ends in circular recesses 21, see Figure 8. These grooves and recesses are to receive the rounded reduced ends 22 of bars 23 of square shape in cross section, the other end of each bar having a reduced part 24 which is of square shape in cross section. The beam 19 carries a plurality of rotary bushings 25, one of which is arranged opposite each recess 21 and the inner end of each bushing has a square recess 26 therein for receiving the square end 24. The outer end of each bushing has a shank 27 extending therefrom of non-circular shape in cross section which receives the pair of collars 28 between which is placed the toothed wheel 29, the parts 28 and 29 being held

on the shank by a nut 30 as more clearly shown in Figure 12. A shaft 31 is journaled in one of the posts which supports the beam 19 and carries a pair of sprockets 32 and a small sprocket 33, a chain 34 passing over the small sprocket and over a sprocket 35 on a shaft 35' rotatably supported on a part of the cover C. A shaft 36 is carried by the sliding block 37 at the other end of the row of wheels 29 and this block can be 10 adjusted by means of a set screw 38. A pair of sprockets 39 is fastened to the shaft 36 and a pair of endless chains 40 pass over the sprockets 32 and 39. Portions of the two chains 40 are connected together by the bars 41 for engaging 15 certain teeth of the wheels 29 so that each time a bar 41 strikes a tooth the wheel will be partly turned and, of course, this motion will be imparted to the bar 23 to which the wheel is attached. By only providing a few of the bars 41 20 the square bars 23 will only be partly rotated at infrequent intervals and by making the drive for shaft 35' a reversible one the chains will cause the square bars 23 to be rotated or partly so first in one direction and then in the other. Of course, 25 the block 37 and the screw 38 provide means for tightening the chains 40. Lower side beams 42 are slidably arranged on the posts 17 and one beam has recesses 43 in its inner face while the other beam has transverse holes 44 passing therethrough. Round rods 45 are adapted to be passed 30 through the holes with one end of each rod engaging a recess 43 and the other end fitting in a hole 44. After the rods 45 are put in place a bar 46, slidably supported on the outer face of the beam 42 which has the holes 44 therein is moved 35 to place the holes 47 therein out of register with the holes 44. Of course, when the rods 45 are to be put in place or removed the sliding bar 46 is adjusted to place its holes 47 in registry with the holes 44. As shown in Figure 5, this sliding bar 40 46 slides through the guides 48 carried by the beam 42 and it is held in the position shown in Figure 5 by the clamping device 49. Each beam 45 can be slidably connected with the posts 17 45 in any suitable manner though I prefer to form notches in the inner portions of the beams 42 through which the posts 17 pass and then plates 42' are fastened to the inner faces of the beams 42 to cover the notches so as to slidably hold the 50 beams to the posts.

Each beam 42 can be adjusted vertically on its posts 17 by means of the handle lever 50 pivoted to one post by a pin 51 which may be placed in any one of a row of holes 52. Diverging links 52 are pivotally connected at their upper ends to an intermediate part of the lever and have their lower ends pivoted to a beam 42 as shown at 53. Each lever is held in adjusted position through means of an arcuate bar 54 depending from a part of the upper portion of the frame and having an arcuate longitudinally extending slot 55 therein, the side walls of which are notched as shown at 56 and a latch button 57 is carried by 55 a handle part 58' rotatably arranged in the lever 50. Thus by turning the part 58' the latch button can be removed from a pair of the notches 56 and the lever adjusted upwardly and downwardly and the latch button placed in another pair of notches as shown more clearly in Figure 10. As shown in Figures 10 and 11 the latch button includes a rectangular part which has a sliding fit in a pair of the notches 56 and a circular part which is connected with a nut 58'' on 70 a threaded part of the shank of the part 58'.

Thus by turning the member 58' in an anti-clockwise direction the nut 58'' will be fed toward the end of the threaded part carrying the button 57 with it until the rectangular part of the button passes out of the space formed by a pair of the notches 56. Then the parts can be adjusted to another pair of notches and the member 58' is turned in a clockwise direction which will cause the nut and button 57 to move inwardly to place the button or the rectangular part thereof in 10 said other pair of notches.

Brackets 59' are carried by the posts adjacent the under parts of the beams 18 and 19 and these brackets support the rods 58 and brackets 59 extend upwardly and inwardly from the beams 42 and support the rods 60. The rods 58 and 60 prevent spreading movement of the yarn supported on the members 23 and 45, as shown in dotted lines at 61 in Figure 3.

It will be seen that the square bars can be raised at their ends which engage the grooves 20 and recesses 21, after the frame has been lifted to the position shown in Figure 1 and the loops of yarn placed over them so that the loops will be suspended from these bars 23. Then the round bars 45 are moved outwardly through the holes 44 after the bar 46 has been adjusted to place its holes in registry with the holes 44 and then these bars 45 are replaced and passed through the lower ends of the loops of yarn after which the bar 46 is moved to the position shown in Figure 5 and locked in position by the clamping device 49. Then the lever 50 is adjusted to cause the bars or rods 45 to properly engage the lower ends of the loops. Then the frame is lowered into the tank, the motor M started to agitate and circulate the dyeing liquid in the tank and the shaft 35' is started to operate the chains 40, the upper reaches of which ride over the collars 28 and every time a rod 41 strikes a tooth of a wheel, said wheel will be partly rotated and this movement will be imparted to the rod 23, the square end of which is placed in the square recess 26 of the bushing 25 being so moved. Thus the loops of yarn are partly revolved at intervals and as before stated by reversing the shaft 35' this partial revolving motion can be reversed.

Uprights 63 extend upwardly from the top of the tank for supporting the cover member C in position shown in Figure 2 and an upright 64 extends upwardly from the top of the tank and carries a stub shaft 67 having a tongue on its inner end for engaging a groove 68 in the shaft 35' when the frame B is in lowered position. A pulley or gear 69 is fastened to the shaft 67 and is suitably connected to a reversible motor, not shown. A removable bar 65 is arranged at one end of the bottom of the frame, said bar being provided with a latch 66 at each end thereof for holding it in position and by removing the bar loading or unloading of the frame is facilitated.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. In a dyeing apparatus, a frame including upper and lower side beams, one of the lower beams having recesses in its inner face and the

other lower beam having holes passing therethrough, round rods adapted to be passed through the holes to place one end of each of which in a recess with the other end of each rod in a hole, 5 a bar slidably arranged on the outer face of the beam having the holes therein and said bar having holes therein for registering with the holes of the beam when the bar is in one position with the holes of the bar moving out of register with 10 the holes of the beam when the bar is in another position, said bar when in the last-mentioned position holding the rods in the two lower beams, one of the upper beams having vertical grooves formed in its inner face terminating at their 15 lower ends in circular recesses, the other upper beam having rotary members therein, the inner end of each of which having a non-circular recess therein, bars of non-circular shape in cross section each having one end reduced and of circular shape in cross section to pass through a 20 groove and to rotatably engage a recess in the grooved and recessed beam, the other end of each

non-circular bar being reduced and of non-circular shape to fit in the non-circular recess of the rotary member, and means for rotating the rotary member.

2. In a dyeing apparatus, a frame including 5 posts, a pair of oppositely arranged upper beams connected with the posts, rotary members supported by the beams, a pair of oppositely arranged lower beams slidably arranged on the posts and paralleling the upper beams, rotary 10 members carried by the lower beams and located under the upper rotary members, a lever for adjusting the lower beams vertically on the posts to adjust the lower rotary members toward or away from the upper rotary members, upwardly 15 and inwardly extending brackets carried by the lower beams and spaced outwardly of the end-most rotary members of the lower beams and rods attached to the upper ends of said brackets for limiting outward movement of material 20 placed on the upper and lower rotary members.

DOMINICK POTTS.
